H. R. CLARKE
TELEPHONE APPARATUS
Filed Jan. 9, 1924

Inventor:
Harry R. Clarke
by ~~W. Adams~~ Atty

UNITED STATES PATENT OFFICE.

HARRY R. CLARKE, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE APPARATUS.

Application filed January 9, 1924. Serial No. 685,163.

To all whom it may concern:

Be it known that I, HARRY R. CLARKE, a citizen of the United States of America, residing at East Orange, in the county of Essex and State of New Jersey, have invented certain new and useful Improvements in Telephone Apparatus, of which the following is a full, clear, concise, and exact description.

10 This invention relates to telephone apparatus and particularly to supports for telephone receivers.

The object of the invention is to provide a light, inexpensive receiver support having 15 a quick detachable head band.

In accordance with the general features of the invention, there is provided a support for telephone receivers consisting of a light head band provided with a hump near 20 one end adapted to rotatably and detachably engage a socket formed by an embossed plate secured to the back of a receiver.

Referring to the drawings, Fig. 1 is a side view of a head receiver embodying the invention. Fig. 2 is a perspective view showing 25 the invention. Fig. 3 is a plan view.

In the drawing 4 represents a well-known type of watch-case receiver, to the back of which is secured by any suitable means, 30 such as screws, 5, a plate 6 having an elongated boss or formed-up portion, centrally located with respect to the back of the receiver. The boss has a deep semi-spherical portion 8 and shallower portions 9 and 10 35 on each side thereof and forms a socket for one end of a head band 12. The portion 10 which extends from the edge of the plate 6 to the spherical portion 8 is preferably rectangular. The boss is preferably provided with a slot 11 extending lengthwise 40 to the edge of the plate 6.

The head band 12 consists preferably of a single flat band of spring steel having an off-set portion 15 substantially the depth of 45 the receiver 4 so that the band 12 will fit snugly to the head and permit a hat to be worn. The end of the head band 12 adapted to engage the socket formed by the plate 6 and the receiver 4 is provided with a hump

13 slightly deeper than the portion 10 of the 50 boss in the plate 6, and preferably slightly shallower than the central portion 8. The band 12 is extended slightly beyond the hump 13 to facilitate its insertion in the 55 socket. When the band is inserted in the socket, the hump 13 is in the portion 8 and the end 16 of the head band is in the portion 9. The height of portion 10 of the 60 boss is preferably slightly less than the width of the band 12 in order to limit the 65 annular movement of the receiver as shown in Fig. 3. The opposite end of the band is provided with a metal pad 14 which may be attached thereto in any suitable manner, such as shearing a boss sufficiently deep to 70 permit the end of the band 12 to force between the inside surface of the boss and the rear of the pad.

What is claimed is:

1. In combination, a telephone receiver, 70 a plate attached to the back of said receiver, said plate having a split boss extending to one edge thereof, and a head band provided with a hump cooperating with said boss whereby it is rotatably and detachably secured between said plate and the back of 75 said receiver.

2. In combination, a telephone receiver, a plate having a depression formed therein extending to the edge thereof, said plate forming with said receiver a socket having a restricted rectangular opening, a flat single strip head band having a hump portion near one end adapted to be inserted in said socket and held therein by its own spring action. 80

3. In combination, a telephone receiver, a plate having a depression therein extending to the edge thereof, said plate forming with said receiver a socket having a restricted rectangular opening, a flat spring head band adapted to engage said socket, said rectangular opening having a depth less than the width of the head band for limiting its angular movement. 85

In witness whereof, I hereunto subscribe 90 my name this 8th day of January A. D., 1924.

HARRY R. CLARKE.
